Primary Examiner — Carol P Rademaker(74) *Attorney, Agent, or Firm* — Birch, Stewart, Kolasch & Birch, LLP(57) **CLAIM**

The ornamental design for a bottle, as shown and described.

DESCRIPTION

FIG. 1 is a top plan view of a bottle showing my new design; FIG. 2 is a front elevational view thereof, the rear, left side, and right side elevational views being identical except for the thread;

FIG. 3 is a front right corner elevational view thereof; the rear left corner elevational view being identical except for the thread; and,

FIG. 4 is a bottom plan view thereof.

The broken lines shown in the drawing views of the inner pour spout surface and of the bottom surface are included for the purpose of illustrating environmental structure and form no part of the claimed design.
